UNITED STATES PATENT OFFICE.

EYVIND LEE HEIDENREICH, OF CHICAGO, ILLINOIS.

FIREPROOF CLUSTER TANKS OF CONCRETE.

SPECIFICATION forming part of Letters Patent No. 667,172, dated January 29, 1901.

Application filed September 28, 1900. Serial No. 31,371. (No model.)

To all whom it may concern:

Be it known that I, EYVIND LEE HEIDENREICH, a resident of Chicago, in the county of Cook and State of Illinois, have invented 5 certain new and useful Improvements in Fireproof Cluster Tanks of Concrete, of which the following is a full, clear, and exact description, reference being had to the accompanying drawings, forming a part of this specification.

This invention has relation to the building of tanks of concrete under those systems—such, for example, as the Monier system—in which the tanks are formed of concrete with 15 suitable metal stay rods or rings embedded therein. My invention consists in building a series or cluster of concrete tanks upon a common concrete base, the base, the tanks, and their "connecting-walls" (by which term 20 is meant the vertical lines of union of the tanks) being formed from an integral homogeneous mass of concrete, so that the finished structure shall be, as it were, monolithic in character or as if carved from a block of stone.

In the accompanying drawings my invention is shown as applied to a cluster or group of twelve tanks mounted upon a common base formed integral therewith; but it is manifest 30 that the number of tanks comprised in the group or cluster may be increased or diminished and the size and thickness of the walls may be varied in correspondence with the size of the tanks and the particular purpose 35 for which they may be designed.

Figure 1 is a view in vertical section upon line 1 1 of Fig. 3. Fig. 2 is a detail view, in vertical section and upon an enlarged scale, showing the upper portion and cover of one 40 of the tanks and showing also a portion of the bottom and of the foundation of such tank. Fig. 3 is a view in horizontal section upon line 3 3 of Fig. 1.

In the practice of this invention the base A, 45 the tank-walls B, and the connecting-walls C are all formed from an integral homogeneous mass of "concrete," by which term a mixture of Portland cement and sand or crushed stone in suitable proportions is commonly 50 designated in the art. Through the base A are extended the horizontal rods D and D', these rods being arranged in the manner com-

monly practiced in the well-known Monier system. In the walls of the tanks B are also arranged horizontal rings or metal stay-rods 55 E, and preferably, also, vertical stay-rods E', the rods being of suitable size, shape, number, and arrangement. Around the top of each of the tanks is extended a Z-shaped annular cap-plate F, that serves to support the 60 individual roof G of the tank, this roof being formed of concrete having stay-rods G' embedded therein. The base A is preferably thicker than the vertical walls of the tanks; but the thickness of the base will depend 65 largely upon the character of the soil or foundation on which the cluster of tanks is erected. Where the tanks are built upon piles, as shown at H on the right-hand side of Fig. 1, the bottoms of the tanks may be formed 70 separate from the foundation proper, as shown at K and K' in Fig. 1, the purpose of this arrangement being to allow the more uniform settling of the bottoms of the tanks with the foundation. When, however, the cluster of 75 tanks is built upon a more solid foundation, the bottoms of the tanks may be formed integral with the base A throughout.

In carrying out the invention the base A will first be formed, the stay rods or wires being set in the concrete at the proper points, and while the concrete of the base is still in plastic condition the walls of the tanks B and the connecting-walls C, uniting the tanks, will be carried up therefrom, the stay rods or 85 wires of the tanks and connecting-walls being properly embedded in the concrete mass as they are erected. When the tanks have been carried to the desired height, an annular Z-bar F will be set in position upon each 90 of the tanks, and the covers G will then be placed above the tanks. It will be understood, of course, that the covers will be provided with suitable openings for the admission of the material with which the tanks will 95 be filled. If it is desired to employ the spaces M between the tanks as receptacles, covers will also be provided for the tops of such spaces. It will be understood also that suitable tap holes or openings may be formed at 100 the bottom of the tanks and the intermediate chambers for the withdrawal of the material therefrom.

In constructing a monolithic cluster of

tanks in accordance with this invention the bodies of the tanks, their foundation, and their connecting-walls being formed from a hardened mass of concrete, every particle of strain delivered at any point of the cluster is distributed throughout the mass, and this is true whether the strains be considered as vertical, due to the weight of the material within any individual tank, or as horizontal, or as the resultant of these strains in any direction. The tanks, their connecting-walls, and their common base being formed of one integral homogeneous mass of hardened material constitute, as it were, a monolithic structure in which every particle of strain delivered to any individual tank is instantly distributed to all parts of the tank cluster and the base. This construction is particularly advantageous where tanks are to be built upon soil of unstable character, since it avoids the necessity of heavy and deeply-laid foundations to resist the strain of the superstructure.

Having thus described my invention, what I claim as new, and desire to secure by Letters Patent, is—

A monolithic cluster of circular fireproof tanks formed of hardened concrete, said tanks being set adjacent each other so as to form intermediate spaces or chambers and upon a common base that extends beneath said tanks and as well also beneath the spaces or chambers between said tanks; said tanks, their connecting-walls and their common base being formed from an integral homogeneous concrete mass, suitable annular stays being embedded in the hardened concrete walls of said tanks and serving to resist the tensile strain from the interior of the tanks and the compression strain from the intermediate spaces.

EYVIND LEE HEIDENREICH.
